UNITED STATES PATENT OFFICE

JOHN LAWERANCE SULLIVAN, OF JERSEY CITY, NEW JERSEY

WINDOW DRESSING ACCESSORY

Application filed April 10, 1931. Serial No. 529,104.

This invention relates to a multiple part structure which may be collectively designated as an accessory or appurtenance for use on a window frame to accommodate and expedite ornamentation and dressing of a window with curtains and draperies.

The particular form of the invention illustrated in the drawings constituting an important part of this application is constructed for use on a window frame of a domestic type which generally embodies upper and lower sliding sashes.

It is now the common practice to provide one or more extensible curtain hangers or rods for the purpose of accommodating panels and drapes. Ordinarily, these curtain rods are made up of telescopically connected adjustable sections detachably mounted on appropriate attaching brackets or fixtures on upper portions of the window frame.

In mounting curtain rods of this kind and applying the fixtures to accommodate the rods, it is generally necessary to climb on a ladder to a convenient elevation to accomplish this task. Obviously, ladder climbing is frequently dangerous and many accidents occur in this class of work.

With the foregoing features in mind, I have conceived of a plan and structure whereby it is possible to attach the curtain rod at a point of comparatively low elevation and to shift the rod to the desired point of elevation and to retain the rod in position until it is desired to lower the same for removal and replacement of curtains, etc.

Briefly enumerated, the preferred embodiment of the invention designed to accomplish this result is characterized by a simple and economical organization of suitable mechanical parts including duplicate devices, and each device embodying a vertical guide and retaining element and a co-operable slide for elevating and lowering and supporting the curtain rod.

In the drawings:

Figure 1 is an inside elevational view of the invention in its assembled and applied form.

Figure 2 is a top plan view of the structure observed in Figure 1.

Figure 3 is a vertical longitudinal sectional view taken on the line 3—3 of Figure 1.

Figure 4 is a perspective view of the relatively fixed guides elements, and

Figure 5 is a perspective view of the relatively adjustable slide.

In the drawings, in Figure 1, the window frame is designated by the numeral 6, and the horizontally disposed sectional and extensible curtain and drapery hanger rods are represented by the numerals 7 and 8. These may be of conventional tubular telescopic design.

In order to accommodate these rods 7 and 8 I provide a pair of duplicate appurtenances or devices as they are the same in construction, a description of one will suffice for both.

I first call attention to Figure 4 wherein it will be noted that the numeral 9 designates one of the two relatively stationary guide elements. This is in the nature of a double channeled plate. The web or plate portion is denoted by the numeral 10 and provided with holes 11 to accommodate the fastener screws 12 as seen in Figure 3.

Each longitudinal edge portion is provided with a parallel guide channel as at 13 and 14. The guide is open at its upper and lower ends to accommodate the slide 15. This slide is in the form of a flexible metal strip whose upper end 16 is beveled and whose lower end is formed with a curvate outwardly bent portion 17 defining what may be designated as a finger grip.

Near its upper end this slide is provided with studs or anchoring pins 18 and 19 to accommodate the laterally curved end portions of the tubular sections of the rods 7 and 8 as is evident in Figure 1. Near the lower end and just above the finger grip 17 is a struck-out tongue 20 which constitutes a retaining detent. This is intended to snap into the slot 21 formed in the plate 10 and serving as a keeper seat.

Attached to the window frame above the guide 9 is a U-shaped bracket 22 designated to receive the bevelled end portion of the slide when deflected therein by the action of the bevel thereon in the extreme upward movement of the slide to provide for stability and rigidity in maintenance of the slide. There

is another U-shaped strap or bracket 23 mounted at the lower part of the guide elements 9, and this bridges the detent equipped portion of the slide 15 as shown in Fig. 3, and when in the lowered positions the members 18 and 19 of the slides engage therewith so as to prevent inadvertent separation of the slides from the guide elements.

In practice it is obvious that the devices 9 10 are to be screwed or otherwise fastened to the window frame in the relative parallel positions represented in Figure 1. When applying or removing draperies the slides 15 are dropped down to the dotted line position represented in this same figure. At this elevation, the pins 18 and 19 are readily accessible to permit expeditious attachment and detachment of the curtain rods 7 and 8.

With the curtains and rods attached the 20 slides 15 can be elevated into full line position represented in Figure 1. In accomplishing this result the finger grips 17 are grasped in such a way as to spring the lower end portion of the slide in each instance to the dotted 25 line position represented in Figure 3 and to snap the retaining detent into the keeper socket 21.

When the slides are completely elevated, the bevelled end portions thereof extend 30 through and slightly beyond the maintenance bracket or strap 22. Consequently, dependability and rigidity is insured with an arrangement of this type and it becomes entirely unnecessary for the user to mount a ladder or to stand on a chair or other uncertain support in hanging draperies.

It is thought that the description taken in connection with the drawings will enable a 40 clear understanding of the invention to be had. Therefore, a more lengthy description is thought unnecessary.

While the preferred embodiment of the invention has been shown and described, it is to be understood that minor changes coming 45 within the field of invention claimed may be resorted to, if desired.

I claim:

1. In a structure of the class described in combination, a slidable plate mountable on a 50 window frame, a curtain rod bracket carried by the upper end portion of said plate, said plate having a beveled upper end, retaining and attaching means on said window frame adapted to slidably accommodate the plate 55 raised and a U-shaped frictional retainer secured upon the window frame above the upper end of the said means, adapted to receive the upper end of the plate when said end is deflected therein by the action of its bevel 60 with the said retainer upon extreme upward movement of the plate.

2. A window frame attachment of the 65 class described comprising a longitudinally elongated guide element including an attach- 130

mental guide channels, a slide mounted for adjustment in said guide channel, and coacting means between the slide and plate to maintain the slide in the up position, the slide extending beyond the upper end of the 70 guide element in extreme up position, and a U-shaped frictional retainer mounted on the window frame above the upper end of the guide element adapted to receive the upper 75 end of the slide deflected therein by the extreme upward movement of the plate so as to maintain the slide against shifting and rattling.

3. A window frame attachment of the class 80 described comprising a longitudinally elongated guide element including an attaching plate having spaced parallel supplemental guide channels, a slide mounted for adjustment in the attaching plate in the guide channels and means coacting between the 85 slide and its plate to maintain the slide in an up position, the slide in its extreme upward position being extended beyond the end of the attaching plate, and a U-shaped frictional retainer mounted on the window frame 90 above the upper end of the attaching plate adapted to receive the upper end of its slide when in the extreme up position and maintain the slide against shifting and rattling, the upper end of the slide being upwardly 95 beveled from the front face thereof to the rear face for deflecting the said upper end of the slide upon entry of the slide in the said U-shaped frictional retainer so that the slide is maintained against shifting and rattling in 100 its extreme upward position.

In testimony whereof I affix my signature.
JOHN LAWERANCE SULLIVAN.
